H. J. COLLIS.

FOB STRAP.

APPLICATION FILED JULY 20, 1911.

Patented Oct. 1, 1912.

UNITED STATES PATENT OFFICE.

HENRY JAMES COLLIS, OF TAUNTON, MASSACHUSETTS.

FOB-STRAP.

1,039,900.

Specification of Letters Patent.

Patented Oct. 1, 1912.

Application filed July 20, 1911. Serial No. 639,640.

To all whom it may concern:

Be it known that I, HENRY JAMES COLLIS, a citizen of the United States, and resident of Taunton, in the county of Bristol and State of Massachusetts, have invented certain new and useful Improvements in Fob-Straps, of which the following is a specification.

This invention relates to fob straps of 10 the class which are employed to carry a watch or other device in the pocket and a pendant or other ornament at the lower end of the portion of the strap which hangs suspended from the pocket.

15 My improvements have particular relation to devices of the class just set forth in which the strap which carries the watch and suspends the pendant is of pliable material, such as leather.

20 The object of my invention is to provide a simple and improved fob strap which will enable the more ready and convenient attachment and detachment of the watch or devices which it carries, which can be readily 25 and economically manufactured, and which will possess advantages in point of security and convenience and facility in use, durability, effectiveness, and general efficiency.

In the drawings—Figure 1 is a face view 30 of a fob device having my improvements. Fig. 2 is a rear view thereof. Fig. 3 is a detail longitudinal sectional view thereof, illustrating the operative action in dotted lines. Fig. 4 is a detail cross-section on 35 the lines α — α , Fig. 3. Fig. 5 is a face view illustrating a modified construction. Fig. 6 is a rear view of the construction shown in Fig. 5. Fig. 7 is a detail longitudinal sectional view of said modified construction.

40 Corresponding parts in all the figures are denoted by the same reference characters.

Referring to the drawings, 1 designates the body of the fob device, which is constituted by a strap of pliable material, preferably leather. The body comprises a top loop, as at 2, for engaging a watch or other article to be worn within the pocket of the user, and a bottom loop, as at 3, for engaging a pendant or ornament or emblem to 45 be suspended from the fob strap outside the pocket. In the construction shown in Figs. 1 to 4, inclusive, the body 1 is constituted by three strips, one of which, 4, forms the top loop 2, and the others of which, 5

and 6 respectively, form the suspending 55 portion and the bottom loop 3. The preferred construction has the top strip 4 turned upon itself to form the loop 2, the back strip 5 turned upon itself at the bottom to form the loop 3 and the front strip 60 6 extending from the lower portion of the top loop 2 to the bottom loop 3. The top ends of the strips 5 and 6 and the rear bottom end of the strip 4 are permanently secured together, and the strip 4 has a free 65 front-end portion, as at 7, and the lower end of the back strip 5 has a free end portion at the front, as at 8, to form the bottom loop 3, over which the lower free end of the front strip 6 projects, as at 9.

70 In the usual constructions heretofore employed, the loops of fob straps of the class to which my invention relates have been secured by buckles embodying the ordinary tongue and perforated strap arrangement. 75 In my present improvements, the loops are secured by a stud and socket means, which not only provides a more ready and convenient and safe fastening but also constitutes the securing means by which the ends 80 of the strips constituting the body 1 are permanently secured together. In the preferred construction, as herein shown in Figs. 1 to 4 inclusive, the securing means for the 85 ends of the strips constituting the body 1 and the fastening means for the top loop 2 comprise a stud device, as at 10, having a back plate or disk, 11, and a front plate or disk, 12, connected with a stud, 14, which passes through the rear bottom end of the 90 strip 4 and the top ends of the strips 5 and 6 and projects beyond the face of the front strip 6, said ends being permanently secured 95 together and clamped between said disks, and the free front end 7 of the strip 4 carries a socket, 15, adapted to engage the projecting portion of said stud 14. A corresponding construction is provided for the bottom loop 3, which comprises a stud, 16, near the lower end of the back strip 5 and 100 projecting from the front face thereof, said stud being connected with a back plate or disk, 17, and a front plate or disk, 18, between which the strip 5 is secured or clamped, and the lower end of the front 105 strip 6 carries a socket, 19, adapted to engage the stud 16, the free end portion 8 of the back strip 5 being provided with a per-

foration, 20, to receive the stud 16 beneath the socket 19.

In the operation of the stud and socket constructions as just described, the top loop 2 and bottom loop 3 are readily operable to enable the detachment and connection of the watch or other device carried in the pocket and the pendant or ornament carried at the lower end of the suspended body 1, and said loops are securely and effectively maintained in closed status.

A safety device, 21, is preferably employed, and is located at the rear side of the body 1 in direct connection with the stud device 10 for the top loop 2. In the preferred construction, the safety device comprises a plate, 22, having at its lower end an opening, 23, receiving the stud 14, said perforated end of the plate 22 being secured 20 and clamped between the back disk 11 of the stud device 10 and the body 1. Said safety device may be in its operative parts of any suitable or adapted construction, but preferably comprises an approximately U-shaped 25 top portion, 24, adapted to receive the edge of the pocket in which the watch is worn, and carrying a cam finger, 25, adapted to compress the fabric at the inner face of the pocket-edge to securely lock the fob strap in 30 connection therewith.

The improved associate construction, as above described, thus comprises composite means for securing the edges of the strips of the body 1 in permanent connection, for 35 fastening the top loop 2, and for securing the fob strap in connection with the pocket of the user.

In the modified construction shown in Figs. 5 to 7 inclusive, the body 1 is constituted by a single strip or strap turned upon itself to form the top loop 2 and the bottom loop 3, one end of said single body-strap being secured by the stud device 10, as at 26, and the other end constituting the free front 45 portion 7 of the top loop 2, carrying the socket 15. In this single strap construction, the pendant or ornament, 27, which is suspended from the fob strap, is permanently retained in the closed bottom loop 3, a securing means being preferably provided in 50 the loop immediately above the pendant, which preferably consists of an eyelet, as at 28, passing through the front and rear portions of the strap at the bottom portion of the loop 3 immediately above the portion of 55 the pendant which engages said loop. The front portion of the body strap may be suitably ornamented in any desired manner, preferably by perforations, as shown at 29, 60 which perforations can be only provided in the front suspended portion of the body 1, as herein shown, or they may extend continuously throughout the body strap if desired.

65 A supplementary safety device, 30, is

preferably employed, in connection with the bottom loop construction 3 of the type shown in Figs. 1 to 3, inclusive, in which the loop is adapted to open for the attachment and detachment of the pendant device 27, for the purpose of retaining said pendant device in secure connection with the loop. In the preferred construction for this purpose, the safety device 30 is constituted by an approximately U-shaped plate, 31, one arm of 70 which, 32, is provided at its top end with an opening, 33, receiving the stud 16, said arm being secured in connection with the pliable body 1 by being clamped beneath the front disk 18 of the stud device 16 and the front 75 face of the back strip 5. The other arm or wing, 34, is shorter than said main arm 32, to form an open mouth, as at 35, to the U-shaped socket, which latter is seated at the bottom of the loop 3 and is adapted to receive the top portion, 36, of the pendant 27, by which the latter is suspended in the loop. For additional safety, the arm 34 is preferably provided with a spring finger struck up 80 from its body and projecting inwardly, as at 85 37, which will act as a lock for the pendant. 90

If desired, the safety device just described may also be employed and correspondingly arranged with relation to the top loop 2, for the purpose of locking the watch or other device which is carried in connection with said top loop.

The operation and advantages of my invention and improvements will be readily understood. The improved fob strap, by reason of its relative construction and arrangement as herein described, provides means for the safe and secure retention of the watch and pendant devices and also enables the more ready and convenient manipulation of the fastened loops in the operation of attaching or detaching the watch and pendant devices. The improved construction also provides a simple means in which the stud fastenings for the loops are 100 combined with and carry supplementary safety devices in conjunction with the fob strap.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. An improved fob strap, comprising a pliable body in strip form, said pliable body constituting a terminal top loop portion 130

- having a free end and also constituting a main portion extending downwardly from said top loop and consisting of a plurality of sections of said pliable body collectively forming a bottom loop portion, and a stud and socket device for securing the free end of said top loop in connection with said main portion of the body, said stud and socket device comprising means at the base 10 of said top loop whereby the plurality of sections of the main portion of the body which form the bottom loop are permanently secured together and means at the free end of said top loop for engagement with said last-mentioned securing means. 15
2. An improved fob strap, comprising a pliable body in strip form, said pliable body constituting a terminal top loop portion having a free end and also constituting a main portion extending downwardly from said top loop and consisting of a plurality of sections of said pliable body collectively forming a bottom loop portion, a stud and socket device for securing the free end of said top 20 loop in connection with said main portion of the body, said stud and socket device comprising means at the base of said top loop whereby the plurality of sections of the main portion of the body which form the bottom loop are permanently secured together and means at the free end of said top loop for engagement with said last-mentioned means, and a safety device carried by said securing means at the base of said top 25 loop and projecting at the rear of said pliable body. 30
3. An improved fob strap, comprising a pliable body in strip form, said pliable body constituting a terminal top loop portion having a free end and also constituting a main portion extending downwardly from said top loop, a stud device carried by said main portion of said pliable body at the base of said top loop and having disks between 35 which the body strip is clamped and from which projects a stud, fastening means carried by the free end of said top loop for engaging said stud, and a safety device secured between the disk of the stud device and the body strip and projecting at the rear of said pliable body. 40
4. An improved fob strap, comprising a pliable body in strip form, said pliable body constituting a terminal top loop portion having a free end and also constituting a main portion extending downwardly from said top loop and consisting of a plurality of sections of said pliable body collectively forming a bottom loop portion, a stud device carried by said pliable body at a point intermediate of said top loop portion and said main lower loop portion, said stud device securing the plurality of sections of the main portion of the body which form the bottom loop portion permanently to- 45
- gether, a socket device carried by the free end of said top loop and adapted to engage said securing stud device, and means for closing the lower loop portion above its terminal lower end whereby a suspended device 70 is retained in position. 50
5. An improved fob strap, comprising a pliable body in strip form, said pliable body constituting a terminal top loop portion having a free end and also constituting a main portion extending downwardly from said top loop and consisting of a plurality of sections of said pliable body collectively forming a bottom loop portion, one of said sections having a free terminal end, a stud device carried by said pliable body at a point intermediate of said top loop portion and said main lower loop portion, said stud device securing the plurality of sections of the main portion of the body which form the bottom loop portion permanently to- 75
- gether, a socket device carried by the free end of said top loop and adapted to engage said securing stud device, and means for closing the lower loop portion above its terminal lower end whereby a suspended device 80 is retained in position. 85
6. An improved fob strap, comprising a pliable body in strip form, said pliable body constituting a terminal loop portion having a free end and also constituting a main portion extending from said terminal loop, a safety device mounted within said loop and secured to and carried by said main portion of the pliable body, and means for fastening the free end of said terminal loop portion in connection with the said main portion of the pliable body at a point beyond said safety device, whereby said safety device is inclosed within said loop and operates to retain a member suspended therein. 90 95
7. An improved fob strap, comprising a pliable body in strip form, said pliable body constituting a terminal loop portion having a free end and also constituting a main portion extending from said terminal loop, a stud device carried by said main portion of the pliable body at the base of said terminal loop, a safety device mounted within said loop and carried by said stud device, whereby said safety device is secured in connection with said main portion of the pliable body, and a socket device carried at the free end of said terminal loop portion and adapted to engage said stud device, whereby said safety device is inclosed within said loop and operates to retain a member suspended therein. 100 105 110
8. An improved fob strap, comprising a pliable body in strip form, said pliable body constituting a terminal top loop portion having a free end and also constituting a main portion extending downwardly from said top loop and consisting of a plurality of sections of said pliable body collectively forming a bottom loop portion, and fasten- 115
- 65 120 125 130

ing means for closing said loop portions, said fastening means comprising a member securing the plurality of sections of the main portion of the body which form the bottom 5 loop portion permanently together and a member at the free end of the loop and engageable with said securing member.

In testimony whereof I have signed my name in the presence of the subscribing witnesses.

HENRY JAMES COLLIS.
